UNITED STATES PATENT OFFICE.

JAMES M. LEAVER, OF LONG BEACH, CALIFORNIA

DRY-KILN FOR LUMBER, &c.

1,108,377.

Specification of Letters Patent. Patented Aug. 25, 1914.

Application filed May 24, 1912. Serial No. 699,578.

To all whom it may concern:

Be it known that I, JAMES M. LEAVER, a citizen of the United States, residing at Long Beach, in the county of Los Angeles and State of California, have invented a new and useful Dry-Kiln for Lumber, &c., of which the following is a specification.

The invention relates to improvements in kilns for drying lumber and other material.

The object of the present invention is to improve the construction of dry kilns, more especially that shown and described in Patent No. 1,039,301, granted to me Sept. 24, 1912, in which a portion of hot moist air from the drying chamber is mixed within the kiln with the outside air before the latter is introduced into the drying chamber, and heated air and moisture is conveyed from the latter to the chimneys or stacks through the medium of suction ducts and suction chambers, and to lessen the cost of construction by the elimination of piers or supports for the rails and the reduced depth of the building.

A further object of the invention is to enable the temperature, moisture and circulation in the kiln to be under more perfect control than heretofore and to prevent absolutely any possibility of near contact of the heating means with the stock to be dried and in conjunction with the improved means of circulation and equalization of temperature to avoid the browning or burning of the stock and the checking and warping and other defects, which frequently result in the lower courses of the lumber when the heating pipes are arranged horizontally at the bottom of the drying chamber.

The invention also has for its object to arrange the heating means to cause an upward passage of air from the outside atmosphere through heating ducts to an overhead mixing chamber and to locate the suction ducts to cooperate with this arrangement of heating means to produce a down draft from the overhead mixing chamber through the drying chamber of heated air from the outside atmosphere and a portion of the hot moist air from the drying chamber in any desired proportions to the total exclusion of hot moist air to obtain a similar result to that produced by the "blower" type kiln, or to the total exclusion of outside atmosphere to cause a recirculation of hot moist air similar to the "com-

pression" plan of drying used in many kilns, and also to obtain between such extremes any desired mixture of outside air and hot moist air required by the stock and any volume of circulation of the same.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings: Figure 1 is a longitudinal sectional view of a portion of a dry kiln, constructed in accordance with this invention. Fig. 2 is a transverse sectional view of the same on the line 2—2 of Fig. 1. Fig. 3 is a similar view on the line 3—3 of Fig. 1. Fig. 4 is a horizontal sectional view on the line 4—4 of Fig. 2. Fig. 5 is a longitudinal sectional view on the line 5—5 of Fig. 2.

Like numerals of reference designate corresponding parts in all the figures of the drawings.

In the accompanying drawings in which is illustrated the preferred embodiment of the invention, the kiln comprises in its construction side walls 1 and 2, designed to be constructed of any suitable material. The dry kiln, which may be constructed in a series, as indicated in Figs. 2 and 3 of the drawings, may, of course, consist of a single drying chamber 4, and it is provided at the top of the same with a horizontal ceiling or top wall 5, spaced from the roof 3 and supported by studding 6 to the underside of which the top wall or ceiling 5 is secured. The intervening space between the roof 3 and the top wall or ceiling 5 is divided by oppositely inclined longitudinally disposed partitions 7 and a central vertical longitudinally disposed partition 8 into outer longitudinally disposed suction chambers 9 and inner longitudinally disposed mixing chambers 10. The partitions 7, which may be of any preferred construction, extend from the opposite side walls of the kiln to the underside of the roof, and their lower side edges are located slightly above the plane of the top wall or ceiling 5 of the drying chamber.

The upper edges of the inclined partitions 7 are preferably spaced from the central vertical longitudinal partition, which extends from the top wall or ceiling 5 to the underside of the roof 3. The side walls 1 and 2, which are hollow, are composed of inner and outer shells, and the interior space between the shells of each of the walls is divided by vertical partitions 11 into alternately arranged heating and suction ducts or passages 12 and 13, extending from the top to the bottom of the drying chamber and communicating, respectively, with the mixing chambers 10 and the suction chambers 9.

15 The kiln is provided with a bottom 14, preferably supported above the surface of the ground by concrete blocks 15 to form an air space 16 below the bottom of the kiln. 20 The bottom of the kiln, which is also hollow, may be constructed of any suitable material, and its interior space is divided into transversely disposed ducts or passages 17 and 18, which extend across the kiln. The 25 lower transverse ducts or passages 17, which communicate at their ends with and connect the lower terminals of the vertical heating ducts or passages, are provided in their lower walls with centrally arranged cold air intake openings 19, communicating with the lower air space 16 for permitting the cold air from the outside atmosphere to enter the kiln and pass through the lower ducts or 30 passages 17 to the vertical heating ducts or passages 12. The upper walls of the lower cold air ducts or passages 17 are provided with centrally arranged openings 20, located at the bottom of the drying chamber and adapted to permit portions of hot moist 35 air from the same to enter the cold air ducts and mix with the air from the outside atmosphere, a preliminary mixing taking place in the lower transverse cold air ducts or passages and in the vertical heating ducts or 40 passages and a final and thorough mixing and commingling occurring in the upper or overhead mixing chambers where the mixture is caused to travel in an approximately circular path and is given a more or less 45 whirling motion before entering the drying chamber, as hereinafter fully explained.

50 The kiln is equipped at the openings 19 and 20 with dampers or valves 21, arranged in pairs and located at opposite sides of the 55 center of the suction ducts and connected by hinges 22 to oppositely inclined partitions or pieces 23 forming approximately inverted V-shaped deflectors, and adapted to separate or divide the moist air from the lower 60 cold air ducts or passages. The dampers or valves and the partitions or deflectors extend entirely across the bottom ducts or 65 passages 17, and the dampers or valves are adapted to be swung upwardly or downwardly from the top to the bottom walls of

the ducts 17 to enable either the hot moist air or the cold outside air to be entirely excluded from the ducts or passages 17 and the dampers or valves are also adapted to be arranged at any intermediate point to obtain the desired proportion of hot moist air and cold outside air to suit the character of the lumber, or other material to be dried. The dampers or valves are connected by links 24 with arms 25 of rock shafts 26, journaled 70 in suitable bearings 27 and extending longitudinally of the kiln and arranged in the air space 16 at opposite sides of the central air intake openings 19. The arms 24 extend inwardly toward the central openings and 75 the links, which are located at opposite sides of the opening, are pivotally connected to the arms 26 and to the valves or dampers 21 and extend through slots 28 in the lower wall of the bottom ducts or passages. The 80 free edge 29 of the valves or dampers are beveled to fit flat against the upper face of the bottom walls of the ducts or passages 17 when the said valves or dampers are at the limit of their downward movement, and they 85 abut against the said bottom walls beyond the slots so as to completely exclude the cold outside air when closed. The longitudinal rock shafts are equipped at one end of the kiln with operating arms 30, and any suitable means may be employed for securing the lower dampers or valves in their adjustment.

85 The vertical heating and suction ducts or passages of the adjacent members of a kiln 100 consisting of a series of units are preferably staggered, as clearly illustrated in Fig. 4 of the drawings, and when all of these ducts are of uniform area, the heating duct of one unit will be located directly opposite the 105 heating duct of the adjacent unit, but they may be constructed of any relative size, the heating ducts or passages being preferably of greater area than the suction ducts or 110 passages, as illustrated in the accompanying drawings. The vertical heating ducts or 115 passages contain heating means adapted to cause an upward draft through the said ducts 16 and consist preferably of steam pipes 31, arranged in the form of radiators, 115 as clearly illustrated in Fig. 5 of the drawings, and connected with longitudinal feed and return pipes 32 and 33, located at opposite sides of the kiln in spaces between 120 stringers 34 and the side walls, the spaces 120 being covered by horizontal walls 35 and divided by transverse partitions 36, which 125 separate the transverse ducts or passages 17 and 18. The longitudinal feed and return pipes 32 and 33 are connected with the vertical heating pipes by branch pipes 37 and 38, equipped with suitable valves 39 and 40, adapted to enable steam or any other heating means to be shut off from any of the vertical 130 heating pipes and this with the main valves

(not shown) of the feed and return pipes places the temperature of the kiln under complete control.

The vertical heating ducts or passages 3 communicate at their upper ends with the mixing chambers 10 at the outer sides thereof, and arranged within the mixing chamber at the outer side portions thereof are inclined deflectors or partitions 41 extending upwardly and inwardly from the side walls and arranged in spaced relation with the top wall or ceiling of the drying chamber and the inclined longitudinal partitions 7 forming upper passages 42 extending upwardly and inwardly from the upper ends of the ducts or passages. The inclined deflectors or partitions 41, which extend the entire length of the drying chambers, are supported by tapered or wedge-shaped pieces 43, and they constitute deflectors and form lower flaring outlets or ducts to vertical side passages 44, located at the top of the drying chamber and formed by deflectors 45. The inclined deflectors or partitions 41 cause the heated air entering the mixing chambers at opposite sides thereof to move upwardly and inwardly and to reverse and pass downwardly and outwardly beneath the said deflectors or partitions 41, as indicated by the arrows in Figs. 2 and 3 of the drawings, thereby producing a partial whirling action, which thoroughly mixes and commingles the hot moist air and the heated air from the outside atmosphere before the latter enters the drying chamber. The tapered or wedge-shaped pieces are suitably mounted upon the studding 6 and extend transversely of the outer portion of the opposite mixing chambers.

The top wall or ceiling 5 terminates short of the side walls of the kiln to provide side openings 46, and the said deflectors 45 depend from the top wall or ceiling 5 at the said openings 46. The deflectors 45, which extend longitudinally of the drying chamber from one end to the other of the same, preferably consist of vertical outer portions 47 and inclined inner portions 48, and the heated air entering the drying chamber at the top at opposite sides thereof travels downwardly and inwardly and passes over and around the lumber, as indicated by the arrows in Figs. 2 and 3 of the drawings. The lumber, which is loaded upon kiln cars 49, extends to the upper portion of the drying chamber to a point above the lower edges of the deflectors, so that the down draft at the center of the load will cause a circulation over the top of the latter. In the accompanying drawings, the lumber is shown piled lengthwise on the kiln cars, but it may be piled in any other desired manner and instead of providing longitudinal side openings 46, which are specially adapted for the lengthwise piling, the openings at the top of

the drying chamber may be arranged in any other desired manner. The down draft at opposite sides of the kiln is increased and the currents are caused to pass along the side walls in the direction of the floor or bottom of the drying chamber, or diverted through the lumber courses by the drawing action of the bottom suction ducts and the hot moist air intake openings when the latter are in use, the down drafts being centralized to produce a current between two loads of lumber. The lower transversely disposed bottom suction ducts 18 are provided in their top walls with central openings 50 and have central vertical partitions 51 dividing the bottom suction ducts and the heated air and moisture entering the ducts or passages 18 and causing the same to travel to the vertical suction ducts or passages 13 at each side of the kiln. The vertical suction ducts or passages 13 communicate at their upper ends with the longitudinal suction ducts 9, which extend the entire length of the kiln and with which are connected chimneys or stacks 52 and 53. The chimneys or stacks may be of any desired number, and the suction chambers 9 may or may not be continuous throughout the entire length of the kiln. The stacks or chimneys, which are hooded, are equipped with dampers or valves 54, and the suction chambers are provided at their top walls with flaring entrances 55 at the lower ends of the chimneys or stacks 52 and 53. The chimneys or stacks 53, which are located at the walls 2, are twice the capacity as the chimneys or stacks 52 and are provided with central vertical partitions 56 forming two passages for the adjacent suction chambers of the contiguous units of the kiln.

The dampers or valves, which are pivotally mounted, may be operated by any suitable means, and by adjusting the dampers or valves of the stack end the dampers or valves of the bottom transverse cold air ducts or passages, the inlet of outside atmospheric air and the escape of the heated air and moisture from the kiln may be controlled. The flexibility or adjustment of this system admits of an infinite variety of treatment of various kinds of wood and in effect covers the entire ground of drying by the exclusive use of outside air to be heated as a circulating medium or such combination of mixed air and moisture as appears best adapted to the requirements of the stock to be dried, whether lumber or other material. The mixing of the hot moist air with the outside air is effected primarily in the transverse bottom ducts or passages, and the lower valves or dampers act as deflectors to direct either or both currents toward the heating pipes, which create an upward draft toward the upper longitudinal mixing chambers.

If the lower valves or dampers are arranged to shut off entirely the hot moist air from the bottom intake openings 20 and air from the outside atmosphere is used exclusively, a result is obtained similar to that produced by kilns of the "blower" type, but without the use of a blower to force the air into the kiln or to draw it out of the same. If the lower valves or dampers are adjusted to close entirely the intake openings to shut off the air from the outside atmosphere and recirculate the hot moist air, the "compression" plan of drying employed in many kilns is attained, the degree of compression being governed by the adjustment of the valves or dampers of the chimneys or stacks. Between these two extremes of adjustment, it is possible to obtain any desired mixture of hot moist air from the drying chamber and the air from the outside atmosphere that may be required by the stock and any volume of circulation up to the full capacity of the ducts and stacks or chimneys and any requisite regulation of the same to suit conditions necessary for perfect drying may be secured.

The stringers 34 support rails 57 of the track for the kiln cars. The stringers are arranged directly upon the bottom of the kiln, and it is unnecessary to support the track at an elevation upon standards or piers to provide a space for the heating means, and the height or depth of the kiln and the consequent cost of the structure are materially decreased by this arrangement. The ends of the drying chamber are closed by suitable doors 58, which may be of any preferred construction.

What is claimed is:—

1. A dry kiln including a drying chamber, a duct or passage extending from the bottom to the top of the kiln and communicating at the bottom with the outside atmosphere and at the top with the interior of the kiln for conducting air from the outside atmosphere to the drying chamber and for introducing it into the same at the upper portion thereof, heating means located exteriorly of the drying chamber and arranged in the path of the said air for heating the same before the air from the outside reaches the drying chamber, a chimney or stack, and a suction duct or passage connected with the chimney or stack and extending to the lower portion of the drying chamber and communicating therewith the interior thereof to produce a positive and continuous down draft in the drying chamber and convey away heated air and moisture therefrom to the chimney or stack.

2. A dry kiln including a drying chamber, means for conducting air from the outside atmosphere to the drying chamber and for introducing such air into the said chamber at the upper portion thereof, means for

heating the said air before the same reaches the drying chamber, means contained within the kiln for mixing a portion of the hot moist air of the drying chamber with the air from the outside atmosphere before the latter enters the drying chamber, a chimney or stack, and a suction duct or passage connected with the chimney or stack and communicating with the drying chamber at the lower portion thereof to carry away the heated air and moisture and to produce a down draft through the drying chamber.

3. A dry kiln including a drying chamber, means for conducting air from the outside atmosphere to the drying chamber and for introducing such air into the said chamber at the upper portion thereof, means for heating the said air before the same reaches the drying chamber, means contained within the kiln for mixing a portion of the hot moist air of the drying chamber with the air from the outside atmosphere before the latter enters the drying chamber, a chimney or stack, a suction duct or passage connected with the chimney or stack and communicating with the drying chamber at the lower portion thereof to carry away the heated air and moisture and to produce a down draft through the drying chamber, and dampers or valves for controlling the admission of outside air and the mixture of the hot moist air with the same and the escape of heated air and moisture through the chimney or stack.

4. A dry kiln including a drying chamber, vertical ducts or passages communicating at their lower ends with the outside atmosphere and connected at their upper ends with the upper portion of the drying chamber, heating means located in the vertical ducts or passages for causing an upward draft through the said ducts and for heating the outside air before the same enters the drying chamber, a chimney or stack, an outlet or suction duct or passage extending from the top to the bottom of the kiln and connected at the upper end with the chimney or stack and communicating at the lower end with the drying chamber at the lower portion thereof to produce a positive and continuous down draft through the drying chamber and carry away heated air and moisture from the same.

5. A dry kiln including a drying chamber, vertical ducts or passages communicating at their lower ends with the outside atmosphere and connected at their upper ends with the upper portion of the drying chamber, heating means located in the vertical ducts for causing an upward draft through the said ducts and for heating the outside air before the same enters the drying chamber, a chimney or stack, means for introducing a portion of hot moist air of the drying chamber into the vertical ducts, a chimney or stack,

and a suction duct connected with the chimney or stack and communicating with the drying chamber at the lower portion thereof to produce a down draft through the said chamber and to permit heated air and moisture to pass therefrom to the stack.

6. A dry kiln including a drying chamber, a suction chamber extending along the top of the kiln, vertical heating ducts extending from the bottom of the kiln to the top of the drying chamber and communicating therewith at the upper portion thereof, heating means located within the heating ducts for causing a positive upward draft through the same, said heating ducts communicating with the outside atmosphere at the bottom of the kiln, a plurality of vertical suction ducts connected with the suction chamber and communicating with the drying chamber at the bottom thereof to produce a positive down draft interiorly of the drying chamber and conveying away heated air and moisture from the same, and a chimney or stack connected with the suction chamber.

7. A dry kiln including a drying chamber, vertical heating and suction ducts located at the sides of the drying chamber, the heating ducts being connected at their upper ends with the upper portion of the drying chamber, bottom mixing ducts located beneath the drying chamber and communicating with the same and with the outside atmosphere, bottom suction ducts connected with the vertical suction ducts and communicating with the lower portion of the drying chamber to produce a down draft therein, a chimney or stack connected with the suction ducts, and heating means arranged in the heating ducts and producing an upward draft through the same.

8. A dry kiln including a drying chamber, vertical heating and suction ducts located at the sides of the drying chamber, the heating ducts communicating with the said chamber at the top thereof, bottom transverse mixing ducts located beneath the drying chamber and communicating with the same and with the outside atmosphere, means for controlling the admission of cold air from the outside atmosphere and hot moist air from the drying chamber to the bottom mixing ducts, and transverse bottom suction ducts also located beneath the drying chambers and communicating with the same and connected with the suction ducts.

9. A dry kiln including a drying chamber, vertical heating ducts located at opposite sides of the drying chamber and communicating at their upper ends with the upper portion of the said chamber, transverse mixing ducts located beneath the drying chamber and connecting the opposite vertical heating ducts and provided with openings communicating with the drying chamber and with the outside atmosphere, dampers or

valves operating at the said openings for controlling the admission of cold air and hot moist air to the bottom mixing ducts, and vertical suction ducts located at the sides of the drying chamber and communicating with the lower portion thereof to produce a down draft within the same.

10. A dry kiln including a drying chamber, vertical heating ducts located at opposite sides of the drying chamber and communicating at their upper ends with the upper portion of the said chamber, transverse mixing ducts located beneath the drying chamber and connecting the opposite vertical heating ducts and provided with openings communicating with the drying chamber and with the outside atmosphere, dampers or valves operating at the said openings for controlling the admission of cold air and hot moist air to the bottom mixing ducts, vertical suction ducts located at opposite sides of the drying chamber, and bottom transverse suction ducts also located beneath the drying chamber and extending across the kiln and connecting the vertical suction ducts and provided with openings communicating with the said drying chamber to produce a down draft through the same.

11. A dry kiln including a drying chamber, vertical heating ducts located at opposite sides of the drying chamber and communicating at the upper ends with the upper portion of the said chamber, transverse bottom ducts connecting the lower ends of the vertical heating ducts and provided with upper and lower openings communicating, respectively, with the said chamber and the outside atmosphere, approximately V-shaped deflectors arranged at the upper openings for dividing the moist air entering the transverse ducts, dampers or valves hinged to the sides of the V-shaped deflectors and movable upwardly and downwardly toward and from the said openings, heating means located within the ducts and creating an upward draft therein, and suction ducts communicating with the lower portion of the drying chamber for producing a down draft through the same.

12. A dry kiln including a drying chamber, vertical heating ducts located at opposite sides of the drying chamber and communicating at the upper ends with the upper portion of the said chamber, transverse bottom ducts connecting the lower ends of the vertical heating ducts and provided with upper and lower openings communicating, respectively, with the said chamber and the outside atmosphere, approximately V-shaped deflectors arranged at the upper openings for dividing the moist air entering the transverse ducts, dampers or valves hinged to the sides of the V-shaped deflectors and movable upwardly and downwardly toward and from the said openings,

- spaced longitudinal rock shafts provided with arms, links connecting the arms with the dampers or valves, heating means located within the heating ducts and producing an upward draft through the same, and suction ducts connected with the drying chamber for causing a down draft therein.
13. A dry kiln including a drying chamber, vertical heating ducts located at opposite sides of the drying chamber and communicating at their upper ends with the upper portion of the same, vertical heating pipes located within the heating ducts and producing a positive upward draft therein exteriorly of the drying chamber, longitudinal pipes located beneath the drying chamber and connected with the vertical heating pipes, vertical suction ducts communicating with the drying chamber at the lower portion thereof and producing a positive and continuous down draft interiorly of the drying chamber and adapted to convey away heated air and moisture therefrom, and means for creating a suction in the said suction ducts.
14. A dry kiln including a drying chamber, vertical heating ducts located at the sides of drying chamber and communicating at their lower portions with the outside atmosphere and connected at their upper portions with the drying chamber at the top thereof, vertical suction ducts located at opposite sides of the drying chamber, and transverse suction ducts extending beneath the drying chamber and connecting the lower ends of the vertical suction ducts and provided with openings communicating with the drying chamber to produce a down draft therein.
15. A dry kiln including a drying chamber, vertical heating ducts located at opposite sides of the drying chamber and communicating at their lower portions with the outside atmosphere and connected at their upper portions with the drying chamber at the top thereof, vertical suction ducts located at opposite sides of the drying chamber and communicating with the outside atmosphere, transverse suction ducts extending beneath the drying chamber and connecting the lower ends of the vertical suction ducts and provided with openings communicating with the drying chamber through the bottom thereof to produce a positive down draft through the same and convey away heated air and moisture from the drying chamber through the bottom openings, longitudinal suction ducts connected with the vertical suction ducts, and chimneys or stacks communicating with the suction ducts.
16. A dry kiln including a drying chamber, vertical heating ducts located at opposite sides of the drying chamber, vertical suction ducts also located at opposite sides of the drying chamber, bottom transverse mixing and suction ducts located beneath the drying chamber and connecting the lower ends of the vertical ducts and having centrally arranged openings communicating with the drying chamber, the said mixing ducts being also provided with openings communicating with the outside atmosphere, heating pipes located within the vertical heating ducts and producing an upward draft through the same, longitudinal mixing chambers located above the drying chamber and communicating with the top portion of the same and connected with the upper ends of the heating ducts, and longitudinal suction chambers located above the drying chamber and connected with the upper ends of the suction ducts.
17. A dry kiln including a drying chamber provided at the top with an opening, a mixing chamber located above the drying chamber and communicating with the same through the said opening, a vertical heating duct connected at its upper end with the mixing chamber and at its lower end with the outside atmosphere, heating means arranged within the heating duct to produce an upward draft through the same, and a suction duct communicating with the lower portion of the drying chamber to produce a down draft therein.
18. A dry kiln including a drying chamber provided at the top with a side opening, a vertical heating duct communicating at its lower portion with the outside atmosphere, heating means located within the heating duct for producing an upward draft through the same, an upper mixing chamber connected with the upper end of the heating duct and communicating with the drying chamber, an inclined deflector extending from the upper end of the heating duct inwardly over the side opening, and a suction duct communicating with the lower portion of the drying chamber to provide a down draft therein.
19. A dry kiln including a chimney or stack, a drying chamber provided at the top with side openings, vertical heating ducts communicating at their lower portions with the outside atmosphere, means for connecting the upper ends of the heating ducts with the side openings of the drying chamber, heating means arranged within the heating ducts and producing an upward draft through the same, and suction ducts connected with the drying chamber at the central portion of the bottom thereof and extending to the side walls and upwardly thereto to the chimney or stack and adapted to produce a positive down draft through the drying chamber and convey away heated air and moisture through the said bottom of the drying chamber.
20. A dry kiln comprising a drying chamber provided at its top with side openings

- and having deflectors depending at the inner sides of the said openings, vertical heating ducts located at the sides of the drying chamber and communicating at their lower portions with the outside atmosphere, means for connecting the upper ends of the heating ducts with the drying chamber including inclined deflectors extending upwardly and inwardly from the upper ends of the heating ducts to points beyond the side openings, and suction ducts communicating with the drying chamber at the central portion of the bottom thereof. 5
21. A dry kiln including side walls, a roof, a top wall or ceiling spaced from the roof and forming a drying chamber and provided with openings, partitions arranged in the space between the roof and the top wall or ceiling and dividing the said space into mixing and suction chambers, the mixing chambers communicating with the drying chamber through the said openings, vertical heating ducts communicating at their upper ends with the drying chambers and at their lower ends with the outside atmosphere, heating means arranged in the heating ducts and producing an upward draft through the same, and suction ducts connected with the suction chambers and communicating with the lower portion of the drying chamber to produce a down draft therein. 10
22. A dry kiln including side walls, a roof, a top wall or ceiling spaced from the roof and forming a drying chamber and provided at opposite sides with openings, partitions dividing the space between the roof and the top wall or ceiling into suction and mixing chambers, the mixing chambers communicating with the drying chamber through the said openings, vertical heating ducts connected at their upper ends with the mixing chambers, heating means arranged within the heating ducts and producing an upward draft through the same, deflectors extending into the drying chambers from the upper ends of the heating ducts and arranged above the side openings of the top wall or ceiling, and suction ducts connected with the suction chambers and communicating with the drying chamber at the lower portion thereof. 15
23. A dry kiln including side walls, a roof, a top wall or ceiling spaced from the roof and forming a drying chamber and provided at opposite sides with openings, partitions dividing the space between the roof and the top wall or ceiling into mixing and suction chambers, the mixing chambers communicating with the drying chamber through the said openings, vertical heating ducts arranged at the sides of the drying chamber and communicating at their lower ends with the outside atmosphere and connected at their upper ends with the mixing chambers, 20 inclined deflectors arranged within the mixing chambers and extending over the said openings from the upper ends of the heating ducts and forming flaring ducts or passages, heating means located within the heating ducts and producing an upward draft through the same, and suction ducts connected with the suction chambers and communicating with the lower portion of the drying chamber to produce a down draft therein. 25
24. A dry kiln including side walls, a roof, a top wall or ceiling spaced from the roof and forming a drying chamber and provided at opposite sides with openings, partitions dividing the space between the roof and the top wall or ceiling into mixing and suction chambers, the mixing chambers communicating with the drying chamber through the said openings, vertical heating ducts arranged at the sides of the drying chamber and communicating at their lower ends with the outside atmosphere and connected at their upper ends with the mixing chambers, partitions or deflectors arranged within the mixing chambers, and extending over the said openings from the upper ends of the heating ducts and forming flaring ducts or passages, heating means located within the heating ducts and producing an upward draft through the same, deflectors depending from the top wall or ceiling at the inner sides of said openings and having vertical outer faces and inclined inner faces, and suction ducts connected with the suction chambers and communicating with the lower portion of the drying chamber. 30
- * 25. A dry kiln including side walls, a roof, a top wall or ceiling spaced from the roof and forming a drying chamber and provided with openings, partitions arranged in the space between the roof and the top wall or ceiling and forming suction and mixing chambers, the mixing chambers communicating with the drying chamber through the said openings, chimneys or stacks connected with the suction chambers, vertical heating and suction ducts located at the sides of the drying chamber and communicating at their upper ends, respectively, with the mixing chambers and the suction chambers, heating means arranged within the heating ducts and producing an upward draft through the same, bottom transverse suction and mixing ducts connecting the lower ends of the vertical ducts and provided in their top walls with openings communicating with the drying chamber, the mixing ducts being also provided with openings communicating with the outside atmosphere, and means for controlling the passage of air through the said ducts. 35
26. A dry kiln including a drying chamber, an upper mixing chamber communicating with the upper portion of the drying 40

chamber, a lower mixing duct located beneath the drying chamber and communicating with the same and with the outside atmosphere and connected with the upper mixing chamber, and a chimney or stack communicating with the drying chamber for producing a circulation in the kiln.

27. A dry kiln including a drying chamber, an upper mixing chamber communicating with the upper portion of the drying chamber, a lower mixing duct located beneath the drying chamber and communicating with the same and with the outside atmosphere, a heating duct having heating means and connected with the lower mixing duct and the upper heating chamber, and a chimney or stack communicating with the drying chamber.

28. A dry kiln including a drying chamber, means for conducting air from the outside atmosphere to the drying chamber and for introducing such air into the drying chamber at the upper portion thereof, means for heating said air to cause a positive upward draft exteriorly of the drying chamber, a chimney or stack, an outlet or suction duct extending downwardly from the top of the kiln to the bottom of the drying chamber and communicating at the upper end with the chimney or stack and at the lower end with the interior of the drying chamber at the lower portion thereof to produce a continuous positive down draft through the drying chamber and positively convey away heated air and moisture therefrom to the bottom thereof, and a damper for controlling the escape of such heated air and moisture.

29. A dry kiln including a drying chamber, vertical ducts or passages located at opposite sides of the drying chamber and extending from the bottom to the top of the kiln and communicating at their lower ends with the interior of the drying chamber at the bottom thereof, a chimney or stack connected with some of the ducts or passages and adapted to create a positive and continuous down draft through the drying chamber, and heating means arranged in other of said ducts or passages to produce a posi-

tive upward draft exteriorly of the drying chamber, the ducts or passages having the heating means being connected at their upper ends with the drying chamber, said kiln being also provided with air inlet openings located at the bottom of the kiln and communicating with some of the said ducts or passages.

30. A dry kiln including a drying chamber, a vertical duct or passage extending from the bottom to the top of the drying chamber and communicating at its ends with the interior of the same, vertical heating pipes arranged in the said duct or passage for creating an up draft through the same, a vertical outlet duct or passage also extending from the top to the bottom of the drying chamber and communicating at its lower end with the interior thereof at the lower portion of the drying chamber to produce a positive down draft, means for creating a suction in the outlet duct or passage, and a damper for controlling the escape of the heated air and moisture from the drying chamber.

31. A dry kiln including a drying chamber, a vertical duct or passage extending from the bottom to the top of the interior of the same, vertical heating pipes arranged in the said duct or passage for creating an up draft through the same, a vertical outlet duct or passage also extending from the top to the bottom of the drying chamber and communicating at its lower end with the interior thereof at the lower portion of the drying chamber to produce a positive down draft, means for creating a suction in the outlet duct or passage, a damper for controlling the escape of the heated air and moisture from the drying chamber, and an air inlet arranged at the bottom of the kiln and communicating with the drying chamber at the top thereof.

In testimony, that I claim the foregoing as my own, I have hereto affixed my signature in the presence of two witnesses.

JAMES M. LEAVER.
